HEM CONSTRUCTION FOR LENGTHENING
DRAPE AND THE LIKE
Nora P. Colignen, Chesterland, Ohio
(11 Neb Hill Drive, Chagrin Falls, Ohio)
Filed Oct. 2, 1962, Ser. No. 227,841
1 Claim. (Cl. 2—243)

This invention relates, as indicated, to a method of and means for lengthening drapes and the like.

In my copending U.S. application, Serial No. 179,432, filed March 13, 1962, now abandoned, there is disclosed a method of and means for lengthening and shortening garments and the like, and which is also described as adapted for use in connection with draperies, bedspreads, valances, etc.

The method, as described in said copending application is particularly adapted for use in connection with lined garments, drapes, etc., but is of little or no utility in connection with unlined drapes.

The present invention has, as its primary object, the provision of a method of and means which is particularly useful for adjusting the length of unlined drapes and the like.

Another object of the invention is to provide a method and means of the character described, in which the material of the drape which is used to provide the hem is secured together at predetermined levels or points by lines of stitching or felling which are substantially concealed from view, yet are easily accessible for removal when the length of the drape is to be adjusted.

Other objects and advantages of my invention will be apparent during the course of the following description.

In the accompanying drawings forming a part of this specification, and in which like numerals are employed to designate like parts throughout the same,

FIG. 1 is a fragmentary elevational view of a drape embodying the invention;

FIG. 2 is a fragmentary cross-sectional view, taken on the line 2—2 of FIG. 1;

FIG. 3 is a view similar to FIG. 2, but with the drape lengthened approximately one inch;

FIG. 4 is a view similar to FIG. 2, but with the drape lengthened about two inches, and

FIG. 5 is a view similar to FIG. 2, but with the drape lengthened about three inches.

Referring more particularly to the drawings, there is disclosed an unlined drape having a front face 1, which is the face normally exposed to the interior of the room in which the drape is hung, and a rear or normally concealed or unexposed face 2.

The drape is provided at its lower edge with a hem which is formed by folding the lower portion of the drape to provide a series of flaps or pleats 3, 4, 5, 6, 7, 8, 9 and 10, all of which lie in planes substantially parallel with the face 2 of the drape and with each other.

The flaps or pleats are formed by folding the material of the drape at points which are designated by reference numerals 11, 12, 13, 14, 15, 16, 17 and 18.

The flap 3 lies in contiguity with the face 2 of the drape, and is one-half inch in height, extending from the fold line 11 to the fold line 12. The flap 4 lies in contiguity with the rear face of the flap 3, and is likewise about one-half inch in height, extending from the fold line 12 to the fold line 13. It may be noted, in this connection, that the fold line 13 is at a slightly higher elevation than is the fold line 11, so that the fold line 13 is concealed from the view of a person viewing the front face 1 of the drape.

The flap 5, which extends from the fold line 13 to the fold line 14, is approximately one inch in height, so that its lower portion lies in contiguity with the rear face of

2

the flap 4, and its upper portion lies in contiguity with the face 2 of the drape.

The flaps 3 and 4 are sewn together, adjacent the fold line 13, as by a line of stitching 19, which stitching is in the nature of felling, that is to say, threads which attach the flaps 3 and 4 securely at the fold line 13, yet can easily be removed by merely pulling one end of the thread. The line of stitching 19 extends parallel with the fold lines 11 and 13.

The flap 6, which extends from the fold line 14 to the fold line 15, is approximately one-half inch in height, so that it lies in contiguity with the rear face of the upper portion of the flap 5.

The flaps 5 and 6 are sewn together, adjacent the fold line 15, as by a line of stitching 20, similar to the stitching 19, and parallel to the latter.

The flap 7, which extends from the fold line 15 to the fold line 16, is approximately one inch in height, so that its lower portion lies in contiguity with the rear face of the flap 6, and its upper portion lies in contiguity with the rear face 2 of the drape.

The flap 8, which extends from the fold line 16 to the fold line 17, is approximately one-half inch in height, so that it lies in contiguity with the rear face of the upper portion of the flap 7.

The flaps 7 and 8 are sewn together, adjacent the fold line 17, as by a line of stitching 21, similar to the stitching 19 and 20, and parallel thereto.

The flap 9, which extends from the fold line 17 to the fold line 18, is approximately one inch in height, so that its lower portion lies in contiguity with the rear face of the flap 8, and its upper portion is substantially co-planar with the flap 8.

The flap 10 extends from the fold line 18 to a point in spaced relation to the fold line 16, and lies in contiguity with the rear face 2 of the drape.

The flaps 9 and 10 are sewn together and to the body of the drape, as by a line of stitching 22, adjacent the fold line 18, and parallel with the lines of stitching 19, 20 and 21.

It may be noted at this point, that in spite of the substantial number of flaps which constitute the hem of the drape, as described, that the flaps are so nested in relation to the body of the drape and in relation to each other, as to increase the thickness of the lower end of the drape to a minor or inconsequential degree, which does not mar or render the drape bulky to an excessive degree.

When it is desired to lengthen the drape one inch, the felling 19 is pulled out, and the flaps 3 and 4 permitted to drop to the position shown in FIG. 3. The fold lines 11, 12 and 13 can then be easily obliterated by pressing the drape in the area of these fold lines.

When it is desired to lengthen the drape two inches, the felling 19, 20 and 21 is pulled out, and the flaps 3, 4, 5, 6, 7 and 8 permitted to drop to the position shown in FIG. 4. The fold lines 11, 12, 13, 14 and 15 can then be easily obliterated by pressing the drape in the area of these fold lines.

When it is desired to lengthen the drape three inches, the felling 19, 20 and 21 is pulled out, and the flaps 3, 4, 5, 6, 7 and 8 permitted to drop to the position shown in FIG. 5. The fold lines 11, 12, 13, 14, 15, 16 and 17 can then be easily obliterated by pressing the drape in the area of these fold lines.

It will be understood that any number of flaps and fold lines may be used, in order to permit lengthening of the drape to an extent greater than provided in the drape shown and described. Moreover, the height of the flaps and the spacing of the fold lines may be varied to permit adjustments in the hem in increments greater or less than that described.

It will also be understood that the drape may be

shortened by a reversal of the described procedure of lengthening the drape.

Although the invention has been described particularly with reference to the lengthening of drapes, it is to be understood that the method and means, as described, is 5 also applicable to unlined skirts, sheath-type dresses, coats, jackets, sleeves, bedspreads, valances, etc.

It is to be understood that the form of my invention, herewith shown and described, is to be taken as a preferred example of the same, and that various changes may 10 be made in the shape, size and arrangement of parts thereof, without departing from the spirit of the invention or the scope of the subjoined claim.

Having thus described my invention, I claim:

An adjustable hem construction for an unlined drapery panel having a front face and a rear face, said construction comprising a plurality of flaps, as follows:

(1) a first flap consisting of three layers of fabric formed from the fabric of said panel by folding said fabric to provide

a first layer of fabric extending upwardly along the rear face of said drapery panel, from a first fold line extending across the width of said panel, along the bottom edge of said panel to a second fold line extending across the width 25 of said panel;

a second layer of fabric extending downwardly and extending along the back of said first layer of fabric and almost to the first fold line and terminating in a third fold line, said third fold line extending across the width of said panel;

a third layer of fabric extending upwardly and having a first portion extending along the back of said downwardly extending second layer of fabric to the second fold line and a second portion extending upwardly beyond said second fold

20

35

line and disposed against the rear face of said drapery panel along a portion substantially equal in length to the length of said first layer of fabric, said second portion constituting the first layer of the next succeeding flap; and a line of removable stitching temporarily binding said first and second layers together along said third fold line;

(2) a plurality of additional flaps each constructed in the same manner as said first flap and extending between said first flap and a final flap, there being a line of removable stitching temporarily binding the first and second layers of fabric in each of said additional flaps along the fold line connecting the second and third layers of fabric of each of said additional flaps;

and (3) a final flap consisting of an upwardly extending extension of the third layer of fabric of the last of said additional flaps, folded over on itself and spaced from the rear face of said drapery panel by the downwardly extending end of said panel which results from said last folding over, and a line of removable stitching temporarily securing the folded over portion of said final flap to said drapery panel.
